UNITED STATES PATENT OFFICE.

ISRAEL GARON, OF DULUTH, MINNESOTA.

TEXTILE FABRIC.

1,373,880.

Specification of Letters Patent.

Patented Apr. 5, 1921.

Application filed December 2, 1919. Serial No. 342,004.

To all whom it may concern:

Be it known that I, ISRAEL GARON, a citizen of the United States, residing at Duluth, in the county of St. Louis and State 5 of Minnesota, have invented certain new and useful Improvements in Textile Fabrics, of which I do hereby declare the following to be a specification.

My invention relates to textile fabrics and 10 has for its object the provision of improvements in elastic woven or knitted textiles. It has for an incidental object the provision of an elastic yarn. With these and other objects in view, it consists of the structures, 15 combinations and arrangements of parts hereinafter described and claimed.

In the drawings, Figure 1, is a cross-section of one form of the hereinafter described elastic yarn forming part of my said invention. Fig. 2 is a side elevation of a piece of 20 said yarn. Fig. 3 is a front elevation of a mitten embodying said invention, and Fig. 4 is a side elevation of a sock, embodying 25 said invention.

In the drawings, 1 is an elastic core of 30 rubber thread, of any suitable cross-sectional shape or contour, upon which is spun a sheath or cover 2 of wool or cotton, or of mixed wool and cotton, or other fibrous material, the manner and method of applying 35 said cover to the rubber core being substantially similar to the manner and method of applying wool to cotton-core yarns, which latter means and methods are well known to the art. That is, the rubber core is led through a spinning machine and the carded wool or cotton is spun upon and around it, the resulting yarn being reeled upon spools. The elastic rubber core yarn forming 40 part of my invention may then be woven or knitted into various products, but I find it especially desirable for use in knitted wrists of mittens, or in the upper ends of socks, or stockings; it may also be used advantageously in knitting the neck portions of turtle-neck sweaters, or the wrist portions of various styles of sweaters, or in the wrist and ankle portions of underwear, and may be used in forming that portion of any knitted 45 garment which is desired to fit the figure closely but nevertheless to yield easily during the operation of putting the garment on or taking it off, or to any muscular pressure from within. A garment may, if desired, be 50 woven or knitted entirely of said rubber-core yarn, or one distinctive portion thereof

may be knitted or woven from said elastic rubber-core yarn and another portion from non-elastic yarn, or said elastic yarn may, in any desired manner, be used in combination or association with non-elastic yarn in a single garment or other textile product, as, for example, the knitting may be done with alternating parallel yarns, one of such yarns being an elastic rubber-core yarn, and the 60 other yarn containing no rubber. In said drawing Fig. 3, shows a mitten, of which the wrist portion 3^a is knitted with said elastic rubber-core yarn from the bottom approximately to the line A—B. The portion 70 3^b of said mitten is preferably knitted of relatively non-elastic yarn, the lower end of which yarn is tied to the upper end of the rubber-core yarn, or the yarns are overlapped at their adjacent ends so that the end 75 of one yarn is for a short distance knitted into the portion of the garment which is otherwise made from the other yarn. Fig. 4 shows a sock, the upper end 4^a of which is preferably knitted with said elastic rubber- 80 core yarn from the upper end approximately to the line C—D, the lower portion 4^b of the sock being preferably knitted with a relatively non-elastic yarn. The portion knitted with said rubber-core yarn is preferably 85 ribbed in the manner well known to the art.

I am aware that certain yarns in which there is no rubber core have, nevertheless, a minor degree of elasticity, but their elasticity is very limited and ephemeral. I am 90 aware also that certain portions of garments, as for example the upper ends of socks are so knitted as to provide ribs or a formation broadly analogous to corrugations by which a considerable degree of temporary elasticity is imparted to such portion of the garment, but such portion quickly stretches out of shape and loses much of its elasticity, while the similar part if knitted with said rubber-core yarn, or alternate rubber-core 100 and other yarn retains its elasticity for a long period. The upper portion of a sock or stocking knitted with a broad band comprising said rubber-core yarn operates as a garter to hold the sock or stocking up, thus 105 making other forms of garters or stocking supports unnecessary in many cases.

Further, it has heretofore been the general practice to knit the wrist portion of a mitten or the upper end of a sock on a different 110 machine from the remaining portion of the mitten or sock, in order to make the wrist or

ribbed portion of less diameter than the adjacent portion so that it will fit snugly. The two parts were then secured together by stitching, or otherwise, thus requiring three 5 operations. By using my elastic yarn, exclusively or as an alternating yarn, for knitting such wrist portion, the wrist portion and the palm portion may be knitted on one machine by a substantially continuous operation, the tension of the elastic yarn contracting the wrist portion.

I am also aware of an elastic webbing in which naked elastic threads are run through, or woven into a fabric consisting chiefly of 15 cotton or silk or wool, but the silk, wool or cotton is not in such case spun upon a core of rubber, and there is therefore not a rubber-core yarn in such webbing.

What I claim is—

20 1. In a yarn, the combination of an elastic

rubber core and a cover of other material spun upon and around said core.

2. In a yarn, the combination of an elastic rubber core and a covering of wool, cotton or other fibrous material spun upon said 25 core.

3. As a new article of manufacture, a yarn comprising an elastic rubber core and a cover of other material spun upon said core.

30 4. As a new article of manufacture, a yarn comprising an elastic rubber core and a cover of fibrous material spun upon and around said core.

In testimony whereof, I hereunto affix my 35 signature, in presence of two witnesses.

ISRAEL GARON.
